IGNITION CONTROL

Joseph J. Mascuch, Maplewood, and Melville F. Peters, East Orange, N. J.

Application September 19, 1950, Serial No. 185,617

20 Claims. (Cl. 315—46)

1

This invention relates to internal combustion engines and particularly to the control of the delivery of fuel igniting sparks across the electrodes of a spark plug constituting a part of the combustion chamber assembly in an internal combustion engine.

In United States patent applications, Nos. 126,771 and 126,772, filed on November 12, 1949 by Melville F. Peters, one of the joint applicants making this present application, it is explained that in the conventional high-tension "series-gap" types of ignition systems there is a substantial amount of electrical energy remaining in the central conductive path of the spark plug after the initial spark discharge across the firing points of the spark plug. In said applications it is also explained that this residual energy frequently creates a reverse potential gradient condition that opposes further flow of current to the spark plug in sufficient strength to produce a second spark discharge across the plug electrodes. It is this impediment to "follow-up" flow that frequently interferes with successful "starting" of an internal combustion engine. The patent applications above-identified disclose methods and means for removing from the high-tension cable the objectionable residual energy above described.

The present invention provides a novel cable terminal construction adapted to serve automatically as a residual energy removing instrumentality, and also as a voltage build-up accelerator for converting the relatively slow build-up rate of the generating unit (spark coil or magneto) into a more rapid build-up rate, effective to reduce substantially the likelihood of misfiring of the spark plug; the novel terminal construction including a tubular grounded conductor of high resistance material and a conductive coupling incorporating a series gap and a series resistance unit intermediate the cable conductor and said series gap. Since the grounded tubular element functions to maintain the central plug conductor at ground potential between firings, it follows that each successive series gap breakdown occurs at a potential that is correspondingly lower than normally would be necessary for such break-down. Because of this ability to fire at lower potential, a spark plug equipped with such a grounded resistor, interposed directly between the series gap coupling and ground, lends itself to high frequency operation, whether it be a conventional plug or a radio-shielded plug; the herein-disclosed terminal being applicable to either type.

2

In the drawings:

Fig. 1 is a longitudinal sectional view of a portion of a radio-shielded spark plug to which is applied a cable terminal embodying the invention;

Fig. 2 is a longitudinal sectional view of a comparable cable terminal applied to a conventional, un-shielded plug; and

Fig. 3 is a circuit diagram explaining the electrical action, in both embodiments.

In the embodiment shown in Fig. 1, the radio-shielding barrel 13 extends upwardly from the base 11, with its wrench-receiving portion 12, and is lined with the usual non-conducting sleeve 9, serving as a socket for reception of the novel cable terminal, attached to the cable in the following manner: The insulation surrounding the lower half-inch (more or less) of the hollow, spirally-wound central conductor 20 of the cable is removed, and a bolt 34 having a longitudinally disposed slot along its shank, to receive the exposed conductor end, is then pressed into the cable center; being preceded by a metal washer 32. A lock washer 33 and nut 30 are then placed on the shank of the bolt 34 and serve to pinch the exposed end of the conductor 20 therebetween by deflecting it side-wise, as illustrated, as the bolt is pushed firmly into place. A bushing 31 of insulating material, with a transversely disposed, centrally apertured shelf, is now slipped over the cable end, until the transverse shelf abuts the nut portion of the bolt. In this position the lower end of the bolt extends downwardly below said shelf to receive the central coupling assembly, consisting of the nut 35, the resistance plug 14, the upper gap element 23, the non-conducting spacer 25, and the lower gap element 24.

The inner diameter of the sleeve 9 lining the plug barrel 13 is somewhat greater than the outer diameter of the bushing 31 containing the central conductive assembly just described. This difference in diameters is taken up by employing, as the high resistance grounding shunt, a tubular element 21, to whose lower end is attached a thimble 41 having a central opening over which the depending knob 42 of the gap element 24 is upset to unite the tube 21 and thimble 41 to the remainder of the cable terminal assembly. The thimble includes a second cylindrical section 43 serving to position the coiled compression spring 44 constituting the conductive coupling between thimble 41 and the head portion 45 of the central conducting spindle 10 whose lower tip constitutes the sparking elec-

trode, or firing point of the plug, as indicated schematically at 18 in Fig. 3. At its upper end the high-resistance shunt tube 21 is flanged to overlie the upper end of the barrel 13, being pressed thereagainst by the action of screwing the cap 46 on the threads of the barrel. Cap 46 presses down on the tube flange by way of the intervening bulge 46 formed in the cable shielding sleeve 48; the cap 46 thus serving as the anchoring means for the cable and its shielding, as well as a conductive coupling between the shielding circuit elements 48 and 13.

The high-resistance shunt tube 21 may be fashioned out of conductive porcelain or other ceramic, conductive rubber or conductive plastic materials other than rubber. The only restrictions are that it be composed of materials whose electrical resistance is less than infinite, and that said materials be such that their resistance decreases as temperature increases.

In the embodiment of Fig. 2 the high-resistance shunt tube 21, like the tube 21 of Fig. 1, is in direct circuit relationship between the grounded spark-plug base 11 and the series gap element 24 of the cable terminal assembly 13-14-23-24, which assembly conductively couples the ventilated cable conductor 20 to the spark plug central electrode spindle 10 by way of conductive coating 14, series gap elements 23-24, and metallic, elbow-shaped, thimble 44' whose lower end embraces the head portion 45' of the electrode spindle 10; the parts 44' and 45' of Fig. 2 thus corresponding in function to the parts 44 and 45 of Fig. 1. Conductive coating 14, applied to the inner surfaces of dielectric sleeve 31, serves as series resistor between the cable conductor 20 and the series gap elements 23, 24. Its resistance value will correspond to that of resistor 14 of Fig. 1.

The high-resistance shunt tube 21 of Fig. 2 will have the same electrical properties, and mode of operation, as the correspondingly numbered tube 21 of Fig. 1; but it will also have sufficient elasticity to permit its being fitted over the cable assembly 20-31-23-24-44 after the relatively rigid metallic fitting 44' has been secured in rivet fashion to the series gap element 24 of the assembly, as indicated at 42. The lower portion of tube 21 is thereafter pushed downwardly over the dielectric body 16 of the plug, until its lower lip 51 snaps under the wrench-receiving bulge 12 of the base 11, to complete the grounding circuit. As this operation is being performed the metallic elbow 44' is simultaneously positioned in embracing relationship to the spark-plug spindle head 45', thus completing the central conductive circuit leading to the spark gap 18-19, by way of spindle 10.

In both embodiments, each sparking cycle is initiated by a build-up of high-frequency energy to the voltage value determined by the dimension of the series gap 23-24; the series resistor 14 also being a factor in this building-up process. When the gap sparking voltage value is reached, energy discharge occurs—first across series gap 23-24, and in predetermined time sequence thereafter across the spark-plug "points" 18, 19. Since the wave front is steep, due to the continuous metallic path from gap element 24 to point 18 (in both embodiments), little energy is lost through grounded high-resistance shunt tube 21 during the brief duration of each spark discharge across 18-19. On the other hand, immediately following cessation of energy flow across gap 18-19, all residual energy remaining in the

central conductive circuit is shunted through the said tube 21 to ground, thus dropping the said central conductive circuit (including the series gap elements 23-24) to ground potential and thereby clearing the central conductive line against any possibility of impeding the voltage build-up for the next succeeding spark discharge cycle.

The use of the high resistance shunt 21 (as in either embodiment) produces high frequency operation because its action in reducing the central conductive circuit to ground potential after every firing cycle makes it possible for the plug to re-fire at a radically lower voltage peak, and hence in a radically shorter time interval. This can be expressed in the form of equations, as follows: Without this shunt 21

$$(1) \quad V = \text{either } \frac{V_1(C_1+C_2)}{C_2} \text{ or } \frac{V_2(C_1+C_2)}{C_1}$$

but by introducing the shunt 21

$$(2) \quad V = \text{either } V_1 \text{ or } V_2$$

In these equations V represents the break-down voltage of the plug (firing point) while V_1 is the break-down voltage of the series gap 23-24; V_2 the break-down voltage of the spark gap; C_1 the capacitance of the series gap; and C_2 the capacitance of the spark gap. If C_1 and C_2 are approximately equal, it follows that the value V obtained from Equation 2 will be only about one-half that of Equation 1, hence successive firings will occur at least twice as frequently, and in practice the frequency gain will be even greater.

As previously noted, the cable conductor 20 is of hollow construction, and all the elements of the plug and cable assemblies are so interfitted as to permit free passage of all developed gases out of the plug cavities by way of said conductor, or into the plug cavities in reverse fashion, for pressurizing. However, the invention is equally effective when applied to a structure wherein the series gap is sealed against entry or emergence of gases, and it is accordingly to be understood that the expression "series gap" in the claims embraces all known types of series gap installations.

What we claim is:

1. In an ignition circuit, a spark plug having a central spindle terminating in a spark discharge electrode, a cable terminal assembly electrically and mechanically coupled to said central spindle, said cable terminal assembly including a combination gap and resistor to ground operating to convert a conventional ignition system into a high-frequency system by draining off to ground, by way of said resistor, all residual energy remaining in said ignition system at the conclusion of a spark discharge at said electrode.

2. In an ignition circuit, a spark plug having a central spindle terminating in a spark discharge electrode, a dielectric body surrounding said spindle, a metallic shell supporting said body, a cable terminal assembly including a metallic thimble forming part of the central conductive path between the cable conductor and said spindle, and means constituting a current path for draining off to ground, by way of said metallic thimble and said shell, any residual energy remaining in said central conductive path at the conclusion of a spark discharge at said electrode.

3. An ignition circuit as defined in claim 2, wherein said draining-off means includes a tubular element forming a direct electrical couple of high resistance between said metallic thimble and said shell.

4. An ignition circuit as defined in claim 2, wherein said cable terminal assembly includes a pair of spaced elements constituting a series gap in said central conductive path, one of said gap elements being integrated with said thimble.

5. An ignition circuit as defined in claim 2, wherein said draining-off means includes a tubular element interposed in telescopic relationship to the shielding extension of the spark-plug shell, and constituting part of the cable terminal assembly.

6. An ignition circuit as defined in claim 2, wherein said draining-off means includes a tubular element whose one end surrounds the cable terminal assembly and whose other end surrounds and attaches to the spark-plug shell.

7. An ignition circuit as defined in claim 2, wherein said draining-off means includes an element having a lower degree of conductivity than said central conductive path.

8. In an ignition circuit, a spark plug having a central spindle terminating in a spark discharge electrode, a cable terminal assembly electrically and mechanically coupled to said central spindle, said cable terminal assembly including a resistor and series gap in the central conductive path leading to said central spindle, and a shunt path to ground of substantially higher resistance than said central conductive path.

9. An ignition circuit as defined in claim 8, wherein said shunt path includes a tubular element forming part of said cable terminal assembly.

10. In an ignition circuit, a spark plug having a central spindle terminating in a spark discharge electrode, and a cable terminal assembly electrically and mechanically coupled to said central spindle, said cable terminal assembly including a pair of resistance elements, one in series with said spindle and the other in shunt.

11. An ignition circuit as defined in claim 10, wherein said series resistance element is a factor in controlling the rapidity of voltage build-up prior to spark discharge, and wherein said shunt resistance element operates to remove residual energy following spark discharge.

12. In an ignition circuit, a spark plug having a central conductive path of pre-determined resistance, and means detachably mounted on the spark plug to establish a shunt path to ground of substantially higher resistance than said central conductive path.

13. An ignition circuit as defined in claim 12, wherein said central conductive path includes a series gap, and wherein said shunt path originates at said series gap.

14. A terminal assembly attachable to an ignition cable and including a residual energy grounding resistor operating to transform a conventional spark generating and discharging system into a high frequency system by increasing the rate of secondary voltage build-up in the central conductive path of the plug.

15. A spark plug cable terminal assembly including a tubular element forming a high resistance couple between the central conductive path of the plug and the grounded outer shell of the plug, and operating to remove from said central conductive path all residual energy remaining therein following spark discharge.

16. A cable terminal assembly as defined in claim 15, and further including a pair of spaced elements forming a series gap, said tubular element being in direct electrical association with said gap elements.

17. A cable terminal assembly as defined in claim 15, wherein said tubular element fits concentrically around the cable, and has detachable connection with the spark plug outer shell.

18. A cable terminal assembly as defined in claim 15, wherein said tubular element extends into the annular space between the end portion of the cable and the surrounding cylindrical extension of the spark plug.

19. A cable terminal assembly as defined in claim 15, wherein said tubular element has a snap-on connection with the spark plug, adjacent its base.

20. In an ignition circuit, a spark plug having a central conductive path, and a cable terminal assembly attachable to said spark plug, said cable terminal assembly including a second conductive path of higher resistance than said central conductive path, but connecting directly therewith.
